UNITED STATES PATENT OFFICE.

SIGMUND L. LEDERER, OF PROVIDENCE, RHODE ISLAND.

CIGAR-TIP CUTTER.

SPECIFICATION forming part of Letters Patent No. 641,024, dated January 9, 1900.

Application filed June 3, 1898. Serial No. 682,443. (No model.)

To all whom it may concern:

Be it known that I, SIGMUND L. LEDERER, of Providence, in the county of Providence and State of Rhode Island, have invented a new and useful Improvement in Cigar-Tip Cutters; and I hereby declare that the following is a full, clear, and exact description of the same, reference being had to the accompanying drawings, forming part of this specification.

This invention has reference to an improvement in the class of cigar-tip cutters adapted for use as a watch-charm or pendant.

The invention consists in the peculiar and novel construction by which the two parts of a rectangular case, adapted to be suspended from a chain, may be operated to cut off the end of a cigar, as will be more fully set forth hereinafter.

Figure 1 is a front view of my improved cigar-tip cutter. Fig. 2 is a top view of the same. Fig. 3 is a side view of the cigar-tip cutter, showing the same in the open position in broken lines. Fig. 4 is a view of the opened end of the same. Fig. 5 is a vertical sectional view of the cigar-tip cutter.

The object of the invention is to utilize the usual rectangular watch-charm and adapt it for use as a cigar-tip cutter.

In the drawings, *a* and *b* indicate two sides of a rectangular box, the closed sides *c c* of which may be ornamented in the manner usual with watch-charms. The upper edges of the two parts *a* and *b* are provided with the round beads *d d*, and the backs at the upper ends are formed with the oblique faces *e e*. The other ends of the two parts of the box have the overlapping slightly curved plates *f f*, provided with the cutters *f' f'*.

A bar *g* extends through holes in a circular projecting part of one part of the box and through the pieces *g' g'*, secured to the other part of the box. A coiled spring *h* extends around the bar *g*, the ends *h' h'* of which bear

on the sides *c c* of the box above the bar *g*. 45 The stirrup *i* is secured to the bar *g*, which extends through the same, and the lower ends of the stirrup *i* are bent inward into notches formed in the parts *a* and *b*, thereby retaining the stirrup *i* in the position shown in Fig. 50 5. Over the obliquely-formed ends of the two parts *a* and *b* of the box a ring *i'* is secured to the stirrup to facilitate the suspension from a watch or other chain.

In the normal position the device has the 55 usual form of a watch-charm. By pressing the upper ends inward against the spring-arms *h' h'* the cutter-plates are separated. The end of a cigar may be inserted and cut off by the strain exerted by the coiled spring 60 *h*, assisted by the pressure of the hand, if required. The round beads *d d* materially facilitate the opening of the cutters, and the flat sides *c c* facilitate the compressing by the hand or by two fingers in cutting off the end 65 of a cigar.

Having thus described my invention, I claim as new and desire to secure by Letters Patent—

In a cigar-tip cutter, the combination with 70 the two parts *a* and *b* forming a receptacle in which the tip end of the cigar is inclosed when cut off, the overlapping curved plates *f f*, the cutters *f' f'*, the beads *d d*, and the oblique edges *e e* on their upper ends, of the bar 75 *g* forming the pivotal connection of the two parts, the coiled spring *h* extending around the bar *g*, the ends bearing on the two parts, and the stirrup *i* provided with the ring *i'*, whereby the device may be suspended from 80 a chain and operated to cut the end of a cigar, as described.

In witness whereof I have hereunto set my hand.

SIGMUND L. LEDERER.
